CLAIM

The ornamental design for a carton, as shown and described.

DESCRIPTION

FIG. 1 is a perspective view of a carton, showing our new design, in a folded and closed configuration.

FIG. 2 is a left elevation view thereof.

FIG. 3 is a right elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a plan view thereof shown in an unfolded configuration; and,

FIG. 9 is a front elevation view thereof, shown in an open configuration.

The portions of the carton shown in broken lines form no part of the claimed design.

1 Claim, 9 Drawing Sheets
